UNITED STATES PATENT OFFICE.

WILLIAM WOLFE, OF ST. LOUIS, MISSOURI.

HEEL-BUILDING MACHINE.

1,122,346.

Specification of Letters Patent.

Patented Dec. 29, 1914.

Application filed January 3, 1911. Serial No. 600,611.

To all whom it may concern:

Be it known that I, WILLIAM WOLFE, a citizen of the United States, residing in the city of St. Louis and State of Missouri, have 5 invented new and useful Improvements in Heel-Building Machines, of which the following is a specification.

This invention relates to improvements in machines employed in building heels and, in 10 a general way, it relates to improvements in the type of machine illustrated in Re-issue Letters-Patent No. 12,433, dated January 2nd, 1906. In said prior patent I described a machine in which a plurality of 15 sectional and independently-adjustable plates was employed for causing the heel blanks to conform to the desired shape, and in conjunction with said plates, which were stationary, I employed a carrier having mounted 20 thereon a gage against which the lifts are piled, after which operation the carrier was caused to be moved inward to force the compiled lifts between and in contact with the plates, whereupon the nail was driven and 25 the heel blank was completed.

Machines constructed according to my said Re-issue Letters-Patent have gone into commercial use and have proven highly satisfactory. I have discovered, however, that the 30 principle of operation employed in said machine is not the best for yielding the highest efficiency with various types and sizes of heels, and that when heels constructed of pieced lifts are to be made, there is always 35 present the liability of the lifts becoming displaced in the movement of the carrier toward the heel former, composed of the adjustable plates referred to. Furthermore, the construction indicated necessitates the use of a 40 relatively large number of working parts, causing the machine, as a whole, to be far more complicated in construction than is desirable.

In the present invention I aim to provide 45 a machine which shall be relatively simple in construction, and which shall be capable of equally advantageous use with all sizes and kinds of heel lifts. The present machine, while embodying certain generic features 50 embraced in my previous invention referred to, such as the independently-adjustable plates composing the heel former, differs radically from said prior invention in the mode of operation; and especially in the fact 55 that I now make the heel gage relatively

stationary and cause the heel former to advance toward and engage about the compiled lifts. By this operation, among other advantages, I obviate the danger of the lifts moving or falling out of position, especially 60 when pieced lifts are used.

The present invention also embodies numerous features of improvement, both as to structural details and mode of operation, which can be better understood from the detailed description to follow. I may, however, mention briefly, that the present invention embodies improved means for positively 65 operating the heel former and nailing mechanism at appropriately-timed intervals; for 70 insuring an easy and accurate movement of the driving mechanism, and for insuring the proper action of the heel former without jar or danger of buckling the lifts.

I have also illustrated in the present case 75 a novel nail-supplying device and connecting parts by means of which it is operatively associated with the nail driving mechanism; and novel mechanism for applying paste to the heel lifts. These latter two improvements are illustrated in connection with the 80 heel building machine for the purpose of showing the general construction and operation of the entire machine. They are not, however, claimed specifically herein, but 85 form the subject-matter, respectively, of separate applications for patents. These applications are identified as follows: paste applying device, Ser. No. 675,657, filed February 5th, 1912; and nailing mechanism for 90 heel building machines, Ser. No. 677,040, filed February 12th, 1912.

In the accompanying drawings—Figure 1 is a view in front elevation of the machine, the lower portion being broken away. Fig. 95 2 is a view in side elevation of the same portion of the machine. Fig. 3 is an enlarged plan view of the heel forming mechanism. Fig. 4 is a vertical longitudinal section of the same. Fig. 5 is an enlarged vertical longitudinal section of the nail guide and compressor. Fig. 6 is a plan view of the same. Fig. 7 is a horizontal section on the line 7—7. of Fig. 5. Fig. 8 is a front elevation of the heel forming mechanism illustrated in Figs. 100 3 and 4. Fig. 9 is a vertical transverse section on the line 9—9 of Fig. 3. Fig. 10 is an enlarged detailed section taken on the line 105 10—10 of Fig. 2, illustrating a portion of the bell crank lever, and of the ram carry- 110

ing the heel former. Fig. 11 is an enlarged horizontal sectional view taken on the line 11—11 of Fig. 2, showing the arm of the bell crank lever, and in connection therewith the 5 sliding members carrying a cam-engaging roller, the view including a portion of the cam. Fig. 12 is an enlarged fragmentary plan view of a portion of the heel forming mechanism, the parts shown being illustrated in their separated position, and a heel 10 constructed of whole lifts being shown in position to be clamped by the heel former preparatory to driving the nail in the heel. Fig. 13 is a view similar to that of Fig. 12, 15 save for the fact that the parts are in a clamped position, and certain portions are in section, the heel illustrated being formed of pieced lifts necessitating the employment of three nails instead of a single nail, such as 20 would be required for nailing the heel shown in Fig. 12. Fig. 14 is an enlarged fragmentary plan view, partly in section, illustrating the clutch mechanism. Fig. 15 is a front elevation of the same, the shaft being in section. Fig. 16 is an enlarged vertical longitudinal section of the clutch mechanism. Fig. 17 is an enlarged front elevation of a portion of the driving bar and its co-operating crank mechanism, and showing in section 25 a portion of the frame of the machine containing a buffing and starting spring for the driving bar. Fig. 18 is an enlarged plan view of a nail receptacle, its conjoined race-ways, flexible nail chutes, and a portion of 30 the machine immediately associated with these parts. Fig. 19 is a vertical longitudinal section taken on the line 19—19 of Fig. 18, and in connection therewith is illustrated the nail releasing mechanism. Fig. 35 40 20 is an enlarged fragmentary front elevation of the mechanism illustrated in Fig. 19, including in addition the means which operate the nail releasing mechanism. Fig. 21 is an enlarged fragmentary plan view of a 45 portion of the bottom of one of the race-ways, showing the nails in position therein, and a spring detent for supporting the lower-most nail; and Fig. 22 is a vertical section taken on the line 22—22 of Fig. 21. 50 Referring now to the drawings, 25 indicates the base or standard of the machine on top of which is mounted the frame 26, supporting the principal working parts. 27 is the main drive shaft which is 55 provided with the ordinary driving pulleys, not shown, whereby the shaft may be continuously rotated. Mounted on the shaft 27 is a sprocket wheel 28. 29 indicates the main driven shaft which 60 has loosely mounted thereon at one end a fly-wheel 32. Secured on the hub of said fly-wheel is a sprocket-wheel 30, and over this sprocket-wheel and the sprocket-wheel 28 is passed a sprocket chain 31. Adjacent 65 to the fly-wheel 32 is a cam-disk 33 having

on its inner face a cam-groove 34. The cam-disk 33 is keyed on the shaft 29 and is revolved at intervals under the control of the operator through the medium of a clutch mechanism, best shown in Figs. 1, 14, 15 and 16. Referring to these figures, 35 indicates a rod which is connected at its lower end to a treadle, not shown, whereby said rod may be raised when it is desired to start the machine. 36 indicates the upper member of a boxing or bearing for one end portion of the shaft 29, said member providing at one side a longitudinally-extending lug 37, which is centrally bored to provide a bearing for a rock shaft 38. 39 indicates an arm which is secured at one end to one end of the rock shaft 38 and is curved under the shaft 29, its outer end being secured to the upper end of the rod 35. On the opposite end of the rock shaft 38 is fixedly secured at one end an arm 40, which at its outer end is inclined on one side to form a wedged portion 41 which terminates at a shoulder or stop 42. 43 indicates a hard metal insert provided on the inner side of the wheel 32 and surrounding the shaft 29, which insert is provided with a recess 44 for receiving the end of a sliding detent 45, which at its opposite end is provided with a lateral rectangular extension 46 which is 85 slidably mounted in a groove 47 formed in a hub 48 of the cam-disk 33, which is also provided with a circumferential groove 49, in which the tapered end of the arm 40 works. A spring 50 housed in the projection 46 of the sliding detent, and bearing against the wall of the recess of the hub 48 in which said projection is mounted, tends normally to press the sliding detent outward so that its outer end will engage in the recess 44 of the fly wheel, which is constantly moving. When this occurs the cam-disk 33 will be caused to rotate with said fly wheel. Normally the outer end of the arm 40 rests in the groove 49, its tapered portion bearing against the end of the projection 46 and holding the sliding detent withdrawn from the recess 44, and the projection 46 also bearing against the shoulder 42 of said arm 40. To place the machine in operation the operator presses on a treadle to raise the rod 35 which, through the medium of the arm 39, rocks the shaft 38, and thereby raises the arm 40 to carry it out of engagement with the projection 46 of the sliding detent; whereupon the spring 50 forces the sliding detent outward and its end will enter the recess 44 and cause the cam-disk 33 to revolve with the fly wheel. As soon as the operator has pressed down on the treadle to release the arm 40 from engagement with the sliding detent he releases the treadle, and the wedge-shaped end of said arm 40 falls into the groove 49. As the hub 48 revolves with the cam-disk it will be seen that 100 105 110 115 120 125 130

as the hub reaches the completion of a single revolution the wedge-shaped end of the arm 40 will engage behind the outer end of the projection 46 causing the sliding detent to be withdrawn from engagement with the recess 44, and, as the projection 46 engages the shoulder 42, stopping the operation of the machine.

The upper portion of a vertical standard 52 of the frame is provided with a slide-way 53 (Fig. 11) in which works a cross-head 54 having suitably mounted thereon a roller 55 which works in a cam-groove 34 of the cam-disk 33. Pivotally mounted in the frame 26, as indicated at 56, (Fig. 2) is a bell crank lever, one arm 57 of which passes through a slot 58, provided in the inner end of the cross-head 54, and at its end is provided with a cross-pin 59, which engages in opposite walls of a slide-box 60, which is slidably mounted in the cross-head 54. In the movement of the cam-disk the cross-head 54 will be alternately lowered and raised, while the slide-box 60 can move back and forth horizontally in said cross-head to permit the outer end of the arm 57 of the bell-crank lever to be raised and lowered.

61 indicates a ram, the rear portion of which is slidably mounted in the standard 52, and which, toward its forward end, is provided with a squared portion 62 which is bifurcated to provide a slide-way 63 for a slide-box 64.

65 indicates the arm of the bell-crank lever complementary to the arm 57, said arm 65 having its end provided with a cross-pin 66, which engages in opposite walls of the slide-box 64. As the bell crank lever is rocked on its pivot 56 the arm 65 will cause the ram 61 to be carried alternately outward and inward, the slide-box 64 having a limited vertical movement in the slide-way 63 of the ram to permit of this operation.

45 The forward end of the ram 61 is enlarged and formed in the shape of a cylinder, such enlarged portion being indicated by 67. The inner end portion of the cylindrical enlargement 67 is externally screw-threaded 50 as indicated at 68, and mounted on said cylindrical portion in engagement with the screw-threads 68 is a collar 69. Slidably mounted on the cylindrical portion 67 is a head 70 carrying the heel formers, and between the rear side of the head 70 and the collar 68 is interposed a coil spring 71. The bed 72 of the machine is provided with a stationary guide 73, having its outer edges undercut, and the head 70 is provided on its 55 under side with a correspondingly-shaped recess to fit the guide 73, such dove-tail connection between the head and the guide being indicated at 74. Extending longitudinally through the guide 73, and located centrally thereof is an aperture 75, the inner

end of which is interiorly screw-threaded to receive an adjusting screw 76. Pivotally mounted at its upper end in the forward end of the cylindrical portion 67 of the ram, as indicated at 77, is a rock-arm 78, the lower 70 end of which, as shown by Fig. 4, is adapted to engage the end of the screw 76, the guide 73 being longitudinally grooved, as indicated at 79, to provide space for the movement of the rock-arm as the ram is reciprocated. The upper end of the rock-arm 78 is forked to provide a yoke 80, in which yoke is pivotally supported from opposite sides a press-block 81. The press-block 81 is mounted to have vertical movement in an extension 82 forming the end of the ram 61, and said extension is cored out to provide an annular space surrounding the press-block 81, in which space is located a coil spring 83. The press-block has a head 84 85 which receives the pressure of the spring 83. The press-block 81 is provided preferably with four vertical apertures, one of said apertures, 85, being located at the center, and the other three apertures, 86, being located near the circumference of the press-block in such manner as to form the points of an imaginary isosceles triangle.

87 indicate spring arms which are secured at one end in grooves formed in the wall of the press block, and have their free ends bent to extend into the apertures 86, as shown clearly in Figs. 5, 6 and 7. A similar spring arm 88 is likewise secured in a groove in the press-block, and has its free end extending through a suitable channel and into the central aperture 85. The purpose of the spring arms 87 and 88 is to retain nails, such as 89, in their respective apertures until such time as said nails are driven into the compiled lifts.

90 indicates a heel gage upon which the lifts are piled up to the requisite height. A lip 91 projecting inward from the top of the gage prevents the top lifts from being forced over the top of the gage under the pressure of the heel former. The bottom 92 of said gage rests upon the guide 73 and is provided with a central hard-metal insert 93, and on its inner side with an upwardly-projecting tongue 94.

95 indicates a casing in which is mounted a hollow plunger 96 capable of a sliding movement in the casing 95, which is limited by means of a set-screw 97, having its end engaging in a recess 98 formed in the upper wall of the plunger. 99 indicates a washer, also mounted in the casing 95, and within the hollow plunger there is housed a coil spring 100 which bears at one end against 120 the closed end of the plunger 96 and at its other end against the washer 99.

101 indicates an adjusting screw which is provided with a non-circular portion 102 (see Figs. 3 and 4) so that a wrench may be 130

applied thereto to adjust the screw to increase or diminish the tension of the spring 100.

103 indicates a bolt having a non-circular end 104, a circular shoulder 105, and beyond said shoulder a screw-threaded end 106. The adjusting screw 101, the washer 99 and the inner end of the plunger 96 are centrally apertured, and the bolt 103 extends through 10 said apertures, and through the coil spring 100, its shoulder 105 resting against the inner end of the plunger, and its screw-threaded portion 106 being screwed into a screw-threaded aperture provided on the front 15 side of the gage 90.

It is contemplated that gages suitable for heels of different sizes and heights will be interchangeably employed in connection with my machine, and to remove one gage 20 and replace another a wrench is applied to the end 104 of the bolt and the same is screwed out of engagement with the gage 90, the substitute gage is put into its place and the bolt turned into screw-threaded engagement therewith. The bolt 103 is capable of a sliding movement in the adjusting screw 101, and the spring 100 will normally press the plunger 96 inward a distance from the casing determined by the length of the slot 25 98, so that the gage 90 will offer a yielding resistance to the pressure of the heel formers as they are brought into contact with the compiled lifts.

The casing 95 is provided with lateral 30 extensions 107 which are in turn provided at their inner ends with vertically-disposed housings 108, said housings and extensions being formed integral with each other and with the casing, respectively. The housings 40 108 are provided with recesses having parallel walls in which are mounted a greater or less number of plates 109 in superimposed relation. Mounted in the upper ends of the housings 108 are clamping screws 45 110, which are provided in their outer ends with non-circular apertures 111 into which a suitably-shaped key may be inserted to turn the screws into engagement with the assembled plates 109 to lock them securely in 50 their adjusted positions. Projecting laterally and forwardly from opposite sides of the front end of the head 70 are integral forked extensions 112 (see Figs. 3, 12 and 13) which provide vertically-disposed housings 113, preferably four in number, similar to the housings 108. These housings are adapted to receive a greater or less number 55 of plates 114 which are clamped to adjusted positions by means of screws 115, similar to the screws 110. By unscrewing the screws 115 the plates 114 may be adjusted in their respective housings to conform to the curvature of a templet of the size of the heel to be made, after which the screws 115 are 60 turned to lock the plates in their adjusted 65

positions. In a similar manner the plates 109 may be adjusted to engage the breast of such templet, and then be locked into position.

The upper surface of the guide 73 is provided toward its outer end with a series of teeth or serrations 116 (see Fig. 4) and the bottom of the casing 95 is similarly serrated. Pivotally mounted on a pin 117, secured at the bottom of the casing 95, are arms 118 (see Fig. 8) in the lower ends of which is mounted a bolt 119. Mounted on the bolt 119 between the arms 118 is a cam 120, provided with a handle 121, the adjustment being such that by moving the handle forward 70 or backward the said cam may be turned into or out of engagement with the under side of the frame of the machine. By releasing the engagement of the cam with the frame the casing 95, and thereby the gage 85 90, and the plates 109, may be moved to adjusted positions relative to the head 70 carrying the heel forming plates 114, and so adjusted may be rapidly clamped into position by turning the handle 121 to cause the 90 engagement of the cam 120 with the under side of the frame, the inter-engagement of the serrations of the guide and the casing 95 assisting in holding the casing in the adjusted position.

I will now proceed to describe the mechanism by means of which the assembled lifts are nailed to the heel; in the case of single lifts, by one nail, as would be the case of the heel illustrated in Fig. 12, or, in the case of 100 pieced lifts, with three nails, as would be the case with the heel illustrated in Fig. 13.

Mounted on the forward end of the shaft 29 is a crank-disk 122, provided with a crank pin 123, on which is mounted a cross-head 124 which works in a transverse slot 124^a formed in an enlargement 125 of a vertically-movable drive-bar 126 carrying in its lower end a driver 127, which is mounted in a removable head 128 through the medium 110 of a block 128^a and a washer 128^b. By removing the head 128, three drivers may be placed in the block if three nails are to be driven, in the case of a heel being built up of pieced lifts, as illustrated in Fig. 13. The 115 drive-bar 126 is mounted to reciprocate in an upper bearing 129 and a lower bearing 130, provided at the extremities of a forked extension 131 forming an integral part of a forward frame member 132. The frame member 132 is bifurcated and laterally extended at its lower end to provide space for the movement of the ram 61 and its head, as indicated at 133 of Fig. 1. Referring to Fig. 17, the drive-bar 126 is provided immediately above the enlargement 125 with a collar 134, and in the upper portion of the bearing 129, which is larger in circumference than the portion of the drive-bar working in said bearing, is a sleeve 135, which is 120 125 130

held in place by a set-screw 136. Between the said sleeve and collar, and encircling the drive-bar, is interposed a coil spring 137, the purpose of which is to act as a combined 5 bumper and actuator. This action will more clearly appear from the description of the operation of the machine to be given later.

The mechanism for supplying nails to be driven into successive heel-blanks comprises 10 the following parts: Mounted on the rock shaft or pivot 56 of the bell crank lever 57-65, is a rock-arm 138, to the outer end of which is pivotally secured one end of a link 139, the opposite end of which is pivotally secured to the bottom side of a receptacle 140 at the rear thereof. Said receptacle is provided with a hinged door 141, by means of which nails may be supplied thereto, and its forward end, along the bottom 15 edge, is pivoted, as indicated at 142, to a stationary race-way 143. The bottom of the receptacle 140 is provided with three slots which are of a width to allow the shanks of nails to fall therethrough, but not wide 20 enough to permit the heads to pass through. As a result, the nails in said slots will be held in a suspended position as shown, as to one of the slots, in Fig. 19. The race-way 143 is provided with three slots 144, which 25 are aline with and, in effect, form continuations of the slots in the bottom of the receptacle 140. The bottom of the race-way 143 is secured to a transverse support 145, in which are inserted from the under side three short 30 tubes 146, the support 145 being slotted to correspond with the slots 144, and the tubes 146 having slots in their sides, as at 147, to permit the nails to enter the same. At the bottom of each of the slots 144 there is secured, by a screw 148, a spring-arm 149, which has a bent end 150 projecting into a vertical aperture 151 forming an enlargement 35 of the bottom of the slot 144, said bent end being slightly below the plane of the upper side of the race-way so that as nails 40 pass down through the slots 144 their shank portion will enter the apertures 151 and their heads rest upon the projecting points 150 of the spring arms. Movable secured to 45 the short tubes 146 are three flexible tubes 152, the lower end portions of which are secured in the ends of arms 153, which are pivotally connected to arms 154, which, in turn, are pivotally mounted in a common 50 support 155. By means of these arms the tubes 152 may be adjusted in position so that their lower ends will be immediately above the apertures 86 of the press-block 81, or so that one of said tubes may be adjusted 55 with its lower end directly over the central aperture 85 of the press-block. The top portion of the race-way is spanned by a bar 156 having three apertures therein directly 60 over the respective slots 144, and when only 65 the central race-way is being used, as indi-

cated in Fig. 18, plugs 157 may be inserted in the two outermost apertures 158 of the bar 156 with their lower ends projecting into the outermost slots 144 of the race-way, whereby to prevent the descent of nails in 70 said slots. As the bell-crank lever 57-65 is rocked back and forth on the pivot 56, the outer end of the rock-arm 138 will be moved alternately up and down and through the medium of the link 139 this motion, which is a sudden or quick motion, will be imparted to the receptacle 140, thoroughly shaking 75 up the nails therein and causing a greater or less number of them to fall into the slots in the bottom of said receptacle. Mounted on the forked member 131 of the frame below the bearing of the shaft 29 is a bracket 159 in which are slidably mounted three vertically-disposed plungers 160, which are secured at their upper ends in a head 161 which is pivotally mounted intermediate the 80 ends of a lever 162. The lever 162 is pivoted at one end on a bearing mounted on the bracket 159, as indicated at 163, and at its other end is provided with a roller 164 which is mounted in the path of a projection 165 carried by some portion of the crank-disk 122, such as the hub thereof, as indicated by 166, shown in dotted lines in Fig. 1, in full lines in Fig. 2, and on an enlarged 85 scale in Fig. 20. Between the head 161 and the bracket 159 are mounted coil springs 167, three of said coil springs being shown, and such springs encircling the respective plungers 160. Each of the plungers 160 carries a nail-releaser 168 which in operation acts to press the head of a nail past a spring arm 149 so that it may fall through one of the tubes 152 into the press-block 81. The operation of these parts will be included in the 90 description of the general operation of the machine.

Referring to Figs. 1 and 2, 169 indicates a receptacle for containing paste. This receptacle is mounted preferably on the right-hand side of the machine, as shown by Fig. 1, and within easy reach of the operator. Mounted in suitable bearings in the sides of the receptacle 169 is a shaft 170, on which is fixedly secured a relatively large roller 171 which is adapted to rotate within the receptacle 169 in a direction toward the machine, and having its bottom located reasonably close to the bottom of the receptacle 169 which is suitably shaped to have a portion 115 of its bottom concentric with the periphery of the said roller. The roller 171 is preferably constructed of wood, but any other suitable material may be employed. 172 indicates a composition roller which is of the same width as the roller 171, and is held in 120 normal engagement with the top of said roller. The roller 172 is mounted at opposite ends in bearings at the upper ends of rods 173 located, respectively, on opposite 125 130

sides of the receptacle 169, said rods being 5
slidably mounted in suitable bearings and
projecting through said bearings into boxes
174, and each rod having at its lower end a
collar 175 between which and the upper end
of the boxes is mounted a coil spring 176,
the purpose of this construction being to
hold the roller 172 in yielding contact with
the roller 171. A series of angle-arms 177
10 are mounted at the side of the machine
proper, and have horizontal extensions 178,
the outer ends of which rest upon, or are
supported in close proximity to the surface
of the roller 171. These arms are located at
15 suitable distances apart throughout the
length of said roller, and if desired, the
latter may be grooved as indicated by the
dotted line in Fig. 1, so that the ends of the
arms 178 will be below the periphery of
20 said roller. Mounted in suitable bearings
provided on a lateral frame-extension 180,
which latter also supports in part the
mechanism just above described, are shafts
carrying rollers 181 and 182, the latter being
25 considerably smaller than the former, and
over which rollers is passed an endless
apron 183, the said rollers and apron being
of the same width, or substantially so, as the
roller 171, and the smaller roller being lo-
30 cated relatively close to the upper part of
the said roller 171. The shaft 170 is suit-
ably connected to a long shaft 184, which
extends to the rear of the machine and is
provided at its end with a sprocket wheel
35 185 which is driven from a suitable sprocket
wheel on the main driving shaft 27 through
the medium of a sprocket chain 186. The
shaft 170 has also secured thereon, outside
of the receptacle 169, a pulley 187, and the
40 shaft 188 on which the roller 181 is mounted
is provided with a pulley 189 over which
pulleys is passed a belt 190. Through the
driving mechanism just described the roller
181, and consequently the apron 183, is
45 caused to revolve. Any preferred means
may be employed for tightening the apron
183. As the roller 171 revolves in the re-
ceptacle 169 it constantly carries up the
paste to the roller 172, which latter is
50 caused to revolve by frictional contact with
the former roller. In use the operator
places a heel lift on the apron 183 which
rapidly discharges it upon the upper sur-
face of the roller 171, which, in turn, carries
55 it underneath the roller 172 and discharges
it on the grate formed by the arms 178
where it may be again picked up by the
operator to be placed in position on the heel
gage. This construction insures the paste
60 being applied equally to both sides of the
lift, and over the entire surface thereof, and
results in great economy in the use of the
paste; and owing to the fact that the paste
is applied uniformly over the entire surface
of both sides of the lift it is only necessary 65
to apply paste to every other lift.
The operation of the machine is as fol-
lows: In the use of the machine the lifts,
or each alternate lift, having been first
passed through the pasting machine are 70
piled up upon the base 92 of the heel gage,
and with the breast of the heel in contact
with the vertical portion 90 thereof. This
operation is continued until the topmost
lift is on a level with the top of the gage, 75
which with the particular heel gage em-
ployed determines the height of the heel.
Referring to the inoperative position of
the machine, such as is illustrated in Figs.
1 and 2, as the heel former has assumed 80
such position, the projection 165 on the hub
of the crank-disk 122 has engaged the roller
at the end of the lever 162 and lowered the
plunger containing the nail releasers 168
so that one or more nails, according to the 85
character of heel being built, has been
forced past the respective spring arms 149
and dropped into the appropriate apertures
86, or the single aperture 85, of the press-
block. The operator now presses on the 90
foot-treadle, raising the rod 35 and thereby
lifting the outer end of the arm 40 to carry
its stop 42 and its wedge-shaped end 41 out
of engagement with the extension 46 of the
sliding detent 45. The latter is now thrown 95
outward by the spring 50 into the recess 44,
thereby locking the cam disk to the con-
stantly-revolving fly-wheel 32, and causing
the former to revolve. As soon as the oper-
ator has depressed the treadle he releases it 100
allowing the end of the arm 40 to fall into
the groove 49 on the hub of the cam-disk.
As the cam-disk is placed in revolution the
cam-groove 34 therein engaging with the
roller 55 causes the outer end of the arm 57 105
of the bell-crank lever to be moved down-
ward and the outer end of the arm 65 of
said bell-crank lever to be thrown outward,
which latter carries the ram 61 with it. In
this operation the adjustable plates 114 con-
stituting the heel former will embrace the 110
sides and rear curved portion of the heel
lifts which latter will be caused to conform
to the shape and configuration previously
determined by an adjustment of said plates 115
114. The engagement of the plates 114
with the lifts is made yielding to prevent
a sudden impact, which operation is effect-
ed by the interposition of the spring 71 be-
tween the ram and the head 70. Also the 120
heel gage is permitted to yield against the
resistance of the coil spring 100 housed in
the plunger 96. As the heel gage recedes
the corners of the heel are permitted to pass
between the ends of the adjustable plates 125
109, thereby insuring the proper conforma-
tion of the lifts at the breast of the heel to
the desired shape determined by the ad-

- justment of the plates 109. As the heel formers are thus carried into clamping position by the head 70, the lower end of the rock-arm 78, which is mounted in the end 5 of the rami, will engage the screw 76, thereby causing the press-block 81 to be brought down upon the assembled lifts and temporarily hold them in a compressed relation. As this occurs the rotation of the 10 shaft 29, through engagement of its crank-pin in the slot 124^a, will cause the drive-bar 126 to descend so that, in the case of a single nail being driven, the driver 127 will enter the aperture 85 and force the nail 89 therein 15 through the compiled lifts, after which said driver will be withdrawn from the press-block under the action of the crank-disk. As previously explained, if a heel of pieced lifts is to be made, three nails would have 20 been fed into the apertures 86 of the press-block and instead of a single driver 127, three drivers would have been mounted in the lower end of the drive-bar 126, and these drivers, in the downward movement of the 25 drive-bar, would have entered the three apertures 86 of the press-block to drive three nails through the assembled lifts, as shown by Fig. 13. As the driver passes out of the press-block the ram is withdrawn 30 under the continued movement of the cam-disk. As this backward movement begins the spring 83 will force the press-block upward out of engagement with the lifts. The backward movement continues until 35 the wedge-shaped end of the arm 40 which is riding in the groove 49 enters behind the extension 46 on the sliding detent 45 and withdraws the same from engagement with the recess 44 of the fly-wheel, after which 40 the shoulder 42 engages the extension 46 and stops further movement of the cam-disk. Ordinarily this stoppage of the cam-disk would be accompanied by considerable jar due to the impact of the extension 46 45 with the shoulder 42, and the consequent sudden arrest of motion of the cam-disk. To obviate this I provide the coil-spring 137, which begins to resist the upward movement of the drive-bar 126 before the 50 engagement of said shoulder and extension. In fact, such engagement does not occur until the crank-pin 123 has passed slightly beyond a dead center, as illustrated in Fig. 17. Thus the maximum compression of the 55 spring is effected just before the extension 46 engages with the shoulder 42, thus cushioning the movement and aiding in bringing the machine to a stop with scarcely any perceptible jar. At the same time, by arranging 60 the relative position of the parts so that the crank-pin 123 will pass slightly beyond a dead center before the machine is brought to a full stop, the coil spring 137 is ready to exert its expansive force to aid in overcoming the inertia of the moving 65 parts when the machine is to be started, thus tending to relieve somewhat the jar and strain of the sudden contact of the wall of the recess 44 with the end of the sliding detent. As the head 70 reaches the rear-most position, just described, another nail 70 will be dropped in the aperture 85 by the mechanism above described, and such nail will be held in the press-block by the spring-arm 88 until the press-block has again been 75 brought into position over the compiled lifts when the nail 89 will be driven through said lifts in the manner described.
- The flexible tubes 152 are preferably formed of coiled wire and are readily adjustable by moving the arms 153 to bring their lower ends over the respective apertures 86, or to bring the lower end of any one of said tubes into position over the central aperture 85 when the press-block is in 85 the rear-most position.
- In the rear or return movement of the ram 61 the top of the yoke 80 engages the head 70 to carry the heel-former away from the gage. In this operation the heel-blank 90 would ordinarily be carried back with the heel-former. To prevent this, I provide the tongue 94, which will hold the blank stationary, and allow the heel-former to pull away from the same. 95
- I claim:
1. In a heel building machine, in combination with a heel-gage, against which the lifts are placed in building up a heel blank, a heel-former reciprocable horizontally in 100 right lines toward and from the heel-gage, and means, under the control of the operator, for automatically actuating said heel-former to cause a single reciprocation thereof. 105
  2. In a heel building machine, in combination with a yieldably-mounted heel-gage, a heel-former movable toward and from said heel-gage, the latter being adapted to controllably yield under pressure of the heel-former on the lifts, and means for reciprocating said heel-former. 110
  3. In a heel-building machine, in combination with a heel-gage, against which the lifts are placed edgewise in building up a heel, a member movable toward and from said heel-gage, a heel-former yieldably mounted on said member and movable thereby into contact with the edges of the lifts to exert, in operation, a yielding pressure on 115 the lifts in shaping the heel blank, and means for imparting a uniform reciprocation to said member. 120
  4. In a heel-building machine, in combination with a yieldably-mounted heel-gage, 125 a member movable toward and from the gage, a heel-former yieldably mounted on said member, said gage and said former be-

- ing adapted to yield under pressure of the latter on the lifts, and means for reciprocating said member.
5. In a heel-building machine, in combination with a heel-gage, against which the lifts are placed edgewise in building up a heel, a member movable toward and from the gage, a spring-pressed heel-former slidably mounted on said member and movable thereby into contact with the edges of the lifts to shape the heel blank, and means for imparting a uniform reciprocation to said member.
10. In a heel building machine, in combination with a heel-gage, a horizontally-movable member, a heel-former carried by said member, a continuously-rotating member, mechanism connected with said horizontally-movable member for reciprocating the same, and means for connecting at will said mechanism with said rotating member to cause the reciprocation of said horizontally-movable member.
15. In a heel building machine, in combination with a heel-gage, a horizontally-movable member, a heel-former carried by said member, a continuously-rotating member, mechanism connected with said horizontally-movable member for reciprocating the same, and means for connecting at will said mechanism with said rotating member to cause the reciprocation of said horizontally-movable member, and means for automatically releasing said connection and stopping the movement after one reciprocation of the horizontally-movable member.
20. In a heel-building machine, in combination with a heel-gage, a heel-former movable bodily in right lines toward and from the heel-gage and comprising a plurality of series of independently-adjustable plates defining, in part, a heel contour, and means, under the control of the operator, for automatically actuating said heel-former to cause a single reciprocation thereof.
25. In a heel-building machine, in combination with a heel-gage, a heel-former movable bodily in right lines toward and from the gage and comprising a head having mounted therein a plurality of series of independently-adjustable plates defining, in part, a heel contour, and means, under the control of the operator, for automatically actuating said heel-former to cause a single reciprocation thereof.
30. In a heel-building machine, in combination with a heel-gage, a member movable toward and from said gage, reciprocating mechanism connected with said member, means for automatically actuating said mechanism to cause a single reciprocation of said member, and a heel-former comprising a head mounted on said member and having movably secured therein a plurality of series of independently adjustable plates.
35. In a heel building machine, in combination with a heel-gage, a heel-former movable toward and from said heel-gage, driving mechanism, means operated thereby for reciprocating said heel-former, and nailing mechanism operated by said driving mechanism in timed relation to the reciprocation of the said heel-former.
40. In a heel building machine, in combination with a heel-gage, a heel-former movable toward and from said heel-gage, means for reciprocating said heel-former, means for supplying nails in driving position relative to the heel-blank on the heel-gage, and nail-driving mechanism operated by the machine in timed relation to the reciprocation of said heel-former.
45. In a heel building machine, in combination with a heel-gage, a heel-former movable toward and from said heel-gage, means for reciprocating said heel-former, nail-supplying mechanism, nail-driving mechanism, and means for operating said mechanisms at timed intervals, respectively, relative to the reciprocation of said heel-former.
50. In a heel building machine, in combination with a heel-gage, a heel-former movable toward and from said heel-gage, means for reciprocating said heel-former, a nail-holder, nail-supplying mechanism and nail-driving mechanism adapted to coöperate with said nail-holder, and means for operating said mechanisms at different times, respectively, relative to the reciprocation of said heel-former.
55. In a heel building machine, in combination with a heel-gage, a heel-former movable toward and from said heel-gage, means for reciprocating said heel-former, a nail-holder movable to a position over the heel-gage, nail-supplying mechanism and nail-driving mechanism adapted to coöperate with said nail-holder, and means for operating said mechanism at different times, respectively, relative to the reciprocation of said heel-former.
60. In a heel building machine, in combination with a heel-gage, a heel-former movable toward and from said heel-gage, means for reciprocating said heel-former, a nail-holder movable with the heel-former, nail-supplying mechanism and nail-driving mechanism adapted to coöperate with said nail-holder, and means for operating said mechanisms at different times, respectively, relative to the reciprocation of said heel-former.
65. In a heel building machine, in combination with a heel-gage, a heel-former movable toward and from said heel-gage, means for reciprocating said heel-former, a nail-holder movable in unison with but independent of the heel-former, nail-supplying mechanism and nail-driving mechanism adapted to coöperate with said nail-holder, and means for operating said mechanisms at dif-

ferent times, respectively, relative to the reciprocation of said heel-former.

18. In a heel building machine, in combination with a heel-gage, a member movable toward and from said heel-gage, a heel-former and a nail-holder carried by said member, means for reciprocating said member, nail-supplying and nail-driving mechanisms adapted to coöperate with said nail-holder, and means for causing such coöperation of the mechanism at the end of the movement of said nail-holder in each direction, respectively.

19. In a heel building machine, in combination with a heel-gage, a reciprocating member movable toward and from said heel-gage, a heel-former and a nail-holder carried by said member, means for reciprocating said member, a driven shaft, nail-supplying and nail-driving mechanisms actuated by said shaft and adapted to coöperate with said nail-holder, the adjustment being such that the nail-supplying mechanism will be actuated to supply a nail to the nail-holder at the end of its movement in one direction, and the nail-driver will be actuated to force the nail therefrom and into the heel-blank at the end of its movement in the opposite direction.

20. In a heel-building machine, a bed, a support adjustably mounted on the bed, a heel-gage mounted on the support, heel-engaging and adjusting devices carried by said support and having operative faces located on opposite sides of the heel-gage, a heel-former movable toward and from said heel-gage, and means for reciprocating said heel-former.

21. In a heel building machine, a support, a heel-gage yieldably mounted thereon, heel-engaging and adjusting devices carried by said support and having operative faces located on opposite sides of the heel-gage, a heel-former movable toward and from said heel-gage, and means for reciprocating said heel-former.

22. In a heel building machine, an adjustable support, a heel-gage yieldably mounted thereon, heel-engaging and adjusting devices carried by said support and having operative faces located on opposite sides of the heel-gage, a yieldably-mounted heel-former movable toward and from said heel-gage, and means for reciprocating said heel-former.

23. In a heel-building machine, a bed, a support adjustably mounted on the bed, a heel-gage mounted on the support, a series of independently adjustable, heel-engaging plates carried by said support at opposite sides thereof, said plates being adjustable relative to the heel-gage, a heel-former movable toward and from said heel-gage, and means for reciprocating said heel-former.

24. In a heel building machine, a support, a heel-gage yieldably mounted thereon, a se-

ries of independently adjustable plates mounted in said support at opposite sides thereof and adjustable endwise toward and from the sides of the heel-gage, a heel-former movable toward and from said heel-gage, and means for reciprocating said heel-former.

25. In a heel building machine, in combination with a heel-gage, a member carrying a heel-former and movable toward and from said heel-gage, a combined press-block and nail-holder slidably mounted in said member and movable thereby to a position over the compiled lifts on the gage, means operating automatically in the movement of said member to force said press-block down upon the compiled lifts, and a nailing device coöperating with said press-block.

26. In a heel building machine, in combination with a heel-gage, a member carrying a heel-former and movable toward and from the heel-gage, a combined press-block and nail-support slidably mounted in said member and movable thereby to a position over the compiled lifts on the gage, means operating automatically in the movement of said member to force said press-block downward upon the compiled lifts, means for supplying a nail to said press-block, and nailing mechanism for operating in the compressing position of the press-block to force the nail therefrom through the compiled lifts on the heel-gage.

27. In a heel building machine, in combination with a heel-gage, a member carrying a heel-former and movable toward and from the heel-gage, a combined press-block and nail-holder yieldably mounted in said member, a holder pivotally supported in said member and connected with said press-block, an arm projecting from said holder, an adjustable stop in the path of said arm whereby in the movement of said member the stop will be engaged by the arm and the holder drawn downward to force the press-block upon the compiled lifts on the heel-gage, means for supplying a nail to said press-block, and a nailing device coöperating with said press-block when the latter is in position on the heel lifts.

28. In a heel building machine, in combination with the bed of the machine, a casing adjustably mounted thereon, a spring-pressed plunger having a limited movement housed in said casing, a heel-gage, means removably connecting the heel-gage to said plunger, a heel-former movable toward and from said heel-gage, and means for reciprocating said heel-former.

29. In a heel building machine, in combination with the bed of the machine, a casing mounted thereon, a spring-pressed support having limited movement housed in said casing, a heel-gage removably connected to said support, means for varying the spring pressure on said support, a heel-

former movable toward and from said heel-gage, and means for reciprocating said heel-former.

30. In a heel building machine, a nail-driver, a nail-support and means for supplying nails thereto, a nail-duct leading from said support, nail-releasing mechanism coöperating with said nail-support, a driven-shaft and means carried thereby for actuating the nail-driver and the nail-releasing mechanism, a heel-gage, a member carrying a heel-former and a nail-holder, and means for reciprocating said member to cause the heel-former to engage the lifts on the heel-gage and the nail-holder to assume a position above said lifts at the termination of the movement of said member in one direction and to carry said nail-holder beneath the nail-duct at the termination of its movement in the opposite direction, the relative arrangement of the parts being such that the nail-releaser will be actuated to supply a nail through said duct to the nail-holder when the latter is beneath the duct, and the nail-driver will be actuated to force the nail from said nail-holder when the latter is above the compiled lifts on the heel-gage.

31. In a heel building machine, in combination with the heel-gage and the heel-former and means for actuating the latter, a paste receptacle carried by the machine and located in convenient proximity to the heel-gage, automatic paste-applying devices operating in connection with said receptacle, and an endless carrier operated continuously from the machine for feeding lifts to said paste-applying devices.

32. In a heel building machine, in combination with a heel-gage, a slidably-mounted ram and means for reciprocating the same toward and from the heel-gage, a collar on said ram, a head slidably mounted on said ram and carrying a series of adjustable heel-formers, a coil spring interposed between said head and said collar, and means for limiting the movement of said head on said ram.

33. In a heel building machine, in combination with a heel-gage, a heel-former coöperating therewith, means for reciprocating the heel-former, a vertically-movable nail driver, means for reciprocating the same, a common drive for said reciprocating means, means for arresting the movement of the heel-former after one cycle of movement, and a spring for cushioning the upward movement of the nail-driver.

34. In a heel building machine, in com-

bination with a heel-gage, a heel-former coöperating therewith, means for reciprocating the heel-former, a vertically-movable nail-driver, means for reciprocating the same, means for arresting the movement of the heel-former after one cycle of movement, and a spring for cushioning the upward movement of the nail-driver, said arresting means becoming effective only after the nail-driver has started to descend.

35. In a heel building machine, in combination with a heel-gage, a heel-former coöperating therewith, means for reciprocating the heel-former, a vertically-movable nail-driver, a crank-disk having a crank-pin for reciprocating the driver, means for arresting the movement of the heel-former after one cycle of movement, and a spring for cushioning the upward movement of the nail-driver, said arresting means becoming effective only after the said crank-pin has crossed the dead center.

36. In combination with a heel-gage, a heel-former coöperating therewith, one of said parts having a movement toward and from the other, and means for causing the heel-blank to be released by the heel-former and to remain on the heel-gage as the latter and the heel-former separate.

37. In combination with a heel-gage, a heel-former coöperating therewith, one of said parts having a movement toward and from the other, and means carried by the heel-gage for causing the heel-blank to be released by the heel-former and to remain on the heel-gage as the latter and the heel-former separate.

38. In combination with a heel-gage, a reciprocating heel-former coöperating therewith, and means carried by the heel-gage for causing the heel-blank to be released by the heel-former and for retaining the heel-blank on the heel-gage as the latter and the heel-former separate.

39. In combination with a heel-gage, a reciprocating heel-former coöperating therewith, and an upwardly-projecting tongue on the side of the heel-gage facing the heel-former for causing the heel-blank to be released by the heel-former and to remain on the heel-gage as the latter and the heel-former separate.

In testimony whereof, I have hereunto set my hand in presence of two subscribing witnesses.

WILLIAM WOLFE.
